ABSTRACT

An articulating frame for a shelter includes a plurality of struts pivotally connected to each other to define a skeletal structure that is adapted to be articulated between a folded condition and an erected condition. The skeletal structure in the erected condition includes a segmented arch that defines an interior space. The skeletal structure is adapted to support an associated outer shell covering. The frame includes at least one double-scissor linkage segment including four of the plurality of struts. The four struts include: (i) first and second struts each with opposite inner and outer ends, the first and second struts being pivotally connected to each other at a first pivot point located between their respective inner and outer ends; and, (ii) third and fourth struts each with opposite inner and outer ends, the third and fourth struts being pivotally connected to each other at a second pivot point located between their respective inner and outer ends. The inner end of the first strut is pivotally connected to the inner end of the third strut at a third pivot point and the inner end of the second strut is pivotally connected to the inner end of the fourth strut at a fourth pivot point such that a four-bar parallelogram accommodating linkage is defined by the four struts between the first pivot point, the second pivot point, the third pivot point, and the fourth pivot point.

ARTICULATING FRAME SHELTER

CROSS-REFERENCE TO RELATED APPLICATION

This application claims priority from and benefit of the filing date of U.S. provisional application Ser. No. 62/781,567 filed Dec. 18, 2018, and the entire disclosure of said provisional application is hereby expressly incorporated by reference into the present specification.

BACKGROUND

Portable, self-supporting, articulating frame shelters are well-known and in widespread use by the military and others. Such articulating frame shelters are collapsible into a relatively compact package that can be stored and transported to a deployment location where the shelter can be quickly deployed or erected and used. The shelter is erected in the field without tools, cranes, power, or other equipment. When fully deployed, the erected shelter comprises a segmented, arched frame including opposite side walls connected by a self-supporting roof span. Examples of such shelters are shown in: U.S. Pat. Nos. 7,481,235; 9,631,393; and, U.S. Patent App. Pub. No. 2017/0247906. As shown in U.S. Pat. No. 9,631,393, the entire disclosure of which is hereby expressly incorporated by reference into the present specification, these shelters are often interconnected in groups making it necessary to have doorways, windows, and other access openings that allow people, equipment, light, and air to travel and flow between the various shelter structures.

These shelter structures comprise a plurality of long, struts that are pivotally interconnected to form an articulating skeletal frame structure. Multiple scissor linkage segments are defined by pairs of struts are pivotally connected at their mid-points by a pin or otherwise to form a generally X-shaped scissor linkage comprising a central pivot point or hinge and four arms that radiate outwardly from the central pivot point/hinge. The frame is constructed by pivotally interconnecting multiple scissor linkage segments (at least two scissor linkage segments) using a hub. The hub, itself, comprises first (upper) and second (lower) hub portions that are releasably interconnected together by a hub post that extends between the first and second hub portions when the frame is erected. The first and second hub portions are selectively separable from each other (with the hub post remaining connected to one of the hub portions) when the frame is collapsed and folded upon itself.

In order for a frame constructed from multiple, interconnected scissor linkages to articulate properly between its collapsed (packed) and expanded (deployed) condition and form an easily packable and transportable cube structure when collapsed, the scissor linkages must all be the same size, i.e., for any two pair of arms of the frame, the sum of the distances (lengths) from the outer pivot point at the distal end of each arm to the central pivot point for the first pair of arms must equal the sum of the distances (lengths) from the outer pivot point at the distal end of each arm to the central pivot point for the second pair of arms. This dimensional scissor-linkage requirement leads to a design trade-off in that longer scissor linkages are often desired for a first part of the shelter frame (e.g., vertical wall regions of the frame that provide doorways or the like for ingress and egress of people and equipment), while for other parts of the frame it is often preferable to use shorter scissor linkages to reduce the overall roof height or to reduce the horizontal span of the

structure. Known articulating frame shelter structures do not allow for mixed-length scissor linkage segments since use of scissor linkage segments of different lengths would prevent the frame from properly articulating as required for collapsing and erecting the frame.

As noted above, the hubs used to join adjacent scissor linkage segments include upper and lower hub portions that must be interconnected through a hub post when the frame is erected. Given that there are multiple hubs that extend along the length and width of the frame, it can sometimes be difficult to align and connect all of the upper and lower hub structures when the frame is being deployed. In particular, the hubs that are located adjacent the ground or other support surface on which the shelter is being erected and that are spaced along the length of the shelter frame on the opposite lateral edges can be particularly problematic to assemble when the shelter is erected. Assembling these hubs quickly and effectively is important in order to erect the shelter quickly as required for military and other applications. As such, a need has been identified for a shelter frame that includes a system for facilitating the assembly of the hubs at least along the opposite lateral edges of the shelter frame.

Another difficulty with erecting known shelter frames relates to the installation of the liner. Known shelter frames include an outer fabric or other flexible membrane that covers the outer surface of the articulating frame and that provides shelter from the external environment such as the weather and other surrounding conditions. It is desirable to further include a liner that covers the internal side of the articulating framework to provide a double-walled structure that has improved thermal insulation, sound insulation, opacity to light, and otherwise generally improves the internal appearance and conditions of the shelter. These liners are typically installed in a manner that results in a sagging appearance due to the excess material or "slack" required to accommodate movement of the articulating frame during the process of erecting the frame. In particular, the liner is typically connected to the frame when the frame is in a partially erected state, and excess liner material is required so that the liner does not become tensioned and resist movement of the frame toward its fully erected state. Any excess material or sagging of the liner is highly undesirable and reduces the effective interior space of the shelter.

As noted, known articulating frames for shelters include a plurality of hubs that each comprise an upper hub portion and a lower hub portion releasably connected together by a hub post. These upper and lower hub portions are disconnected from each other when the shelter is collapsed and folded. When the frame is erected, these hubs are required to resist heavy loads from wind, snow, and the like, but must also be capable of being assembled without tools in the field. Known hub structures have been found to be generally effective, but a need has been identified for a new and improved hub for an articulating frame shelter that is easy to assemble and that provides even better strength, rigidity, and resistance to separation of the upper and lower hub components.

Another drawback with known articulating frame shelters is that any door structure defined in the shelters includes a scissor linkage that extends across the threshold of the door opening. The threshold scissor linkage is necessary in order for the articulating frame to maintain its alignment when it is being erected or collapsed. Once the shelter frame is fully erected, the presence of the threshold scissor linkage is undesirable for several reasons. This threshold scissor linkage can present a tripping hazard to those walking into and out of the shelter. Furthermore, a cart or vehicle entering the

shelter must roll over the threshold scissor linkage and can damage same. As such, a need has been identified for an articulating frame shelter that overcomes these issues.

SUMMARY

According to a first embodiment of the present development, an articulating frame for a shelter includes a plurality of struts pivotally connected to each other to define a skeletal structure that is adapted to be articulated between a folded condition and an erected condition. The skeletal structure in said erected condition comprises a segmented arch that defines an interior space. The segmented arch skeletal structure is adapted to support an associated outer shell covering. The frame includes at least one double-scissor linkage segment comprising four of the plurality of struts. The four struts include: (i) first and second struts each comprising opposite inner and outer ends, the first and second struts being pivotally connected to each other at a first pivot point located between their respective inner and outer ends; and, (ii) third and fourth struts each comprising opposite inner and outer ends, the third and fourth struts being pivotally connected to each other at a second pivot point located between their respective inner and outer ends. The inner end of the first strut is pivotally connected to the inner end of the third strut at a third pivot point and the inner end of the second strut is pivotally connected to the inner end of the fourth strut at a fourth pivot point such that a four-bar parallelogram accommodating linkage is defined by the four struts between the first pivot point, the second pivot point, the third pivot point, and the fourth pivot point.

In another embodiment, a double-scissor linkage for a shelter frame comprises four struts including: (i) first and second struts each comprising opposite inner and outer ends, the first and second struts being pivotally connected to each other at a first pivot point located between their respective inner and outer ends; and, (ii) third and fourth struts each comprising opposite inner and outer ends, the third and fourth struts being pivotally connected to each other at a second pivot point located between their respective inner and outer ends. The inner end of the first strut is pivotally connected to the inner end of the third strut at a third pivot point and the inner end of the second strut is pivotally connected to the inner end of the fourth strut at a fourth pivot point such that a four-bar parallelogram accommodating linkage is defined by the four struts between the first pivot point, the second pivot point, the third pivot point, and the fourth pivot point.

BRIEF DESCRIPTION OF THE DRAWINGS

FIG. 1 is an isometric view of an articulating frame shelter constructed in accordance with an embodiment of the present development (partially showing the flexible outer shell covering), with the frame fully erected/deployed;

FIG. 2 is a first end view of the shelter of FIG. 1 (the opposite end view is substantially identical);

FIG. 3 shows the frame of FIGS. 1 & 2 in a fully collapsed, folded, or packed state in which it forms a cubic structure for storage and transport (the flexible outer shell covering is not shown in FIG. 3);

FIG. 4 shows the frame of FIGS. 1 & 2 in a partially collapsed or partially deployed state between its fully collapsed and fully deployed configurations (the flexible outer shell covering is not shown in FIG. 4);

FIG. 4A illustrates an enlarged portion of FIG. 4 and shows a double-scissor linkage constructed according to an embodiment of the present invention;

FIG. 5A partially illustrates another view of the double-scissor linkage of FIG. 4A and shows a hard stop knee hinge portion of the double-scissor linkage;

FIG. 5B illustrates a frame formed in accordance with the present development and is labeled to illustrate certain structural relationships required for the frame to articulate between its stored and deployed conditions;

FIG. 6 shows detail region 6 of FIG. 1 with the shelter frame in the partially erected/deployed configuration and shows a ground strap cinch system according to an embodiment of the present invention;

FIG. 7 is an end view of a shelter provided in accordance with an embodiment of the present invention including the outer shell and also including optional inner liner, and including a dynamic liner cinching system;

FIG. 8 illustrates an embodiment of the dynamic liner cinching system of the present invention;

FIGS. 9 and 10 partially show a shelter frame according to the present invention and illustrate an embodiment of the hub structure thereof, with FIG. 9 showing the frame partially deployed/erected and FIG. 10 showing the frame fully deployed/erected;

FIGS. 11A & 11B are views of the shelter frame of FIG. 1 showing an optional folding or pivoting door threshold structure in its extended (down) and retracted (up) positions, respectively.

DETAILED DESCRIPTION OF THE INVENTION

As shown in FIGS. 1-6, a shelter 10 provided in accordance with an embodiment of the present development comprises an articulating frame 20 and an outer covering or outer shell S connected to an outer side of the frame 20. When erected as shown in FIG. 1, an inner skeletal surface of the frame 20 defines a hollow interior space IS for sheltering people, equipment, animals, and other resources from weather and other external environmental conditions. With brief reference to FIG. 7, the shelter 10 optionally comprises an inner liner LN comprising a flexible fabric or similar covering that is connected to the inner side of the frame 20 such that the inner liner LN and outer shell S define a double-walled covering for the shelter 10, with the frame 20 located in the space between the outer shell S and the inner liner LN.

With continuing reference to FIGS. 1-6, the frame 20 comprises a plurality of struts 22,72 that are pivotally connected to each other such that the frame 20 can articulate from a folded position or condition shown in FIG. 3 to the fully erected position or condition shown in FIGS. 1 & 2, through an intermediate (partially erected/partially folded) position or condition shown in FIG. 4. The fully erected frame 20 defines a skeletal structure that supports the outer shell S and the optional inner liner LN. The frame struts 22,72 are typically defined from a strong, lightweight metal such as aluminum and are generally tubular in structure, but the struts can be solid and/or can be defined from any other suitable metallic and/or non-metallic strut material such as fiberglass, carbon fiber, wood, and/or polymeric materials. The pivoting connections are provided by rivets, pins, bolts, or other suitable fasteners or pivoting connections.

As shown in FIGS. 1 & 2, the erected frame 20 defines a length FL between its opposite front and rear ends 20a,20b, and defines a width FW between its opposite left and right

5

lateral sides **20c,20d**. The width FW is measured where the opposite lateral sides **20c,20d** of the frame **20** contact the floor, ground, or other support surface GR on which the frame **20** is supported.

The frame **20** comprises left and right side walls **30a,30b** each comprising and defined by a plurality of rectangular wall sections **30s**. In the illustrated example, the left and right side walls **30a,30b** are identical to each other but arranged in a mirror image fashion relative to each other. The frame **20** further comprises a roof **40** comprising and defined by multiple roof spans **40a, 40b, 40c** that each extend along the length **FL** of the frame and that each comprise a plurality of rectangular roof sections **40s**.

The wall sections **30s** and roof sections **40s** each comprises a plurality of primary scissor linkage segments **50**. Each primary scissor linkage segment **50** comprises a pair of identical first and second struts **22a,22b** (generally **22**) pivotally connected to each other between their opposite outer ends **54** at their respective mid-points by a pin or the like to form a generally X-shaped scissor linkage comprising a central or inner pivot point **50P**. Each individual primary scissor linkage segment **50** defines a first length **50L** when the shelter frame **20** is fully erected. The first length **50L** can be measured in a straight line between the respective outer ends **54** of the first and second struts **22** between successive hubs **60**.

The primary scissor linkage segments **50** are pivotally interconnected to each other by a plurality of hubs **60**. Each hub **60** comprises an upper hub portion **62**, and lower hub portion **64** spaced-apart from the upper hub portion **62**, and a post **66** that extends between and interconnects the upper and lower hub portions **62,64**. The post **66** is fixedly secured at one end to the lower hub **64** (or upper hub **62**) and is selectively, releasably secured to the opposite upper hub **62** (or lower hub **64**) when the frame **20** is erected. The upper and lower hub portions **62,64** are each respectively pivotally connected two or more struts **22**, at the outer ends of each primary scissor linkage segment **50** spaced from the internal scissor pivot point **50P** as indicated at first, second, third, and fourth pivot points respectively labeled **Q1,Q2,Q3,Q4**.

In the illustrated embodiment, roof **40** of the frame **20** comprises a plurality of the primary scissor linkage segments **50** arranged in a rectangular grid or matrix to define the plurality of rectangular roof sections **50s**, wherein each span **40a,40b,40c** of the roof **40** comprises a column of adjacent roof sections **40s**.

According to the present invention, the walls **30** of the frame **20** are constructed to have a height or "eave height" **EH** (FIG. 2) that is greater than the length **50L** of each primary scissor linkage segment **50**, while still permitting the frame **20** to articulate as needed between its folded position (FIG. 3) and its erected position (FIGS. 1 & 2). This is accomplished by defining each wall section **30s** to include first and second double-scissor linkage segments **70** that are vertically oriented and located on the opposite lateral sides of each wall section **30s** and that are connected by upper and lower horizontally extending primary scissor linkage segments **50** (or that are connected by upper and lower horizontally extending double-scissor linkage segments **70**). As such, for each wall section **30s**, a first one **70a** of the double-scissor linkage segments **70** is located closer to the front end **20a** of the frame **20** and a second one **70b** of the double-scissor linkage segments **70** is located closer to the rear end **20b** of the frame **20**. The double-scissor linkage segments **70** define a second length **70L** when the frame **20** is erected which equals the eave height **EH**, and this second length **70L** is greater than the first length **50L** of the primary

6

scissor linkage segments **50** ($70L > 50L$) so that eave height **EH** is always at least equal to the second length **70L** and is always greater than the first length **50L** of the primary scissor linkage segments **50**. The second length **70L** can be measured in a straight line between successive hubs **60** and between the outer end **74** of the second strut **72b** and the outer end **74** of the fourth strut **72d**.

Despite its longer length **70L**, a double-scissor linkage segment **70** is able to articulate as needed with the primary scissor linkage segments **50** of frame **20** because each double-scissor linkage segment **70** comprises a central accommodating linkage **AK** that provides additional length to each double-scissor linkage segment **70** when the frame **20** is erected and but that folds or articulates to accommodate or absorbs the additional length when the frame is folded.

As shown in the enlarged view of the partially erected frame in FIG. 4A, the double-scissor linkage segments **70** each comprise four elongated struts **72** (i.e., **72a,72b,72c,72d**) that are identical to the struts **22** of the primary scissor linkage segments **50** except that the elongated struts **72** are longer than the struts **22** of the primary scissor linkage segments **50**. The struts **72** (**72a,72b,72c,72d**) can be as little as 1 inch or less longer than the struts **22** or as much as twice the length or more than the struts **22** without departing from the scope and intent of the present development, with these variations limited by the space required to accommodate the joints (for very small added lengths) and by the required structural stability (for very large added lengths). First and second ones of the elongated struts **72a,72b** are respectively connected at their outer ends **74** to the upper and lower hub portions **62,64** of an outer hub **60a** and are pivotally connected to each other at a first pivot point **P1** where they intersect between their opposite outer and inner ends **74,76**. The first pivot point **P1** need not be centrally located on the struts **72a,72b** and is located closer to the strut inner ends **76** in the illustrated example. Furthermore, the distance between the outer end **74** and the first pivot point **P1** need not be the same for both the first and second struts **72a,72b**; and (ii) the distance between the inner end **76** and the first pivot point **P1** need not be the same for both the first and second struts **72a,72b**.

Similarly, the third and fourth struts **72c,72d** are respectively connected at their outer ends **74** to the upper and lower hub portions **62,64** of an inner hub **60b** and are pivotally connected to each other at a second pivot point **P2** where they intersect between their opposite outer and inner ends **74,76**. The distance between the outer end **74** and the second pivot point **P2** need not be the same for both the third and fourth struts **72c,72d**; and (ii) the distance between the inner end **76** and the second pivot point **P2** need not be the same for both the third and fourth struts **72c,72d**.

For ease of reference herein, the pivot points where the first and second elongated struts **72a,72b** are respectively connected at their outer ends **74** to the upper and lower hub portions **62,64** of the outer hub **60a** are respectively labeled **P5,P6** in FIGS. 4A and 5B, and the pivot points wherein the third and fourth struts **72c,72d** are respectively connected at their outer ends **74** to the upper and lower hub portions **62,64** of the inner hub **60b** are respectively labeled **P7,P8** in FIGS. 4A and 5B.

The inner ends **76** of the first and third elongated struts **72a,72c** are pivotally interconnected at a third pivot point **P3**, and the inner ends **76** of the second and fourth elongated struts **72b,72d** are pivotally interconnected at a fourth pivot point **P4** such that the first, second, third, and fourth pivot

points P1-P4 and the portions of the elongated struts 72 that extend therebetween define a four-bar parallelogram accommodating linkage AK.

It should be noted that a first sum of the distances (lengths) of the portions of the elongated struts 72a,72b that extend between the pivot points adjacent outer hub 60a and the first pivot point P1 is equal to a second sum of the distances (lengths) of the portions of the elongated struts 72c,72d that extend between the pivot points adjacent inner hub 60b and the second pivot point P2. Furthermore, these distances (the first sum and the second sum) are also each equal to a third sum of distances (lengths) defined along the struts 22 between the pivot points Q1,Q2,Q3,Q4 adjacent each hub 60 and the internal pivot point 50P of the primary scissor linkage segments 50, which allows the frame 20 to articulate between its folded and erected positions. Each accommodating linkage AK thus adds length to the double-scissor linkage segments 70 when the frame 20 is erected and absorbs or removes length from the double-scissor linkage segments 70 when the frame 20 is folded. This allows the double-scissor linkage segments 70 of length 70L to be used in a frame 20 that includes shorter, primary scissor linkage segments 50 of length 50L where needed to increase the length or width of the wall segments 30s or roof segments 40s while still allowing the frame 20 to articulate into a cube configuration as shown in FIG. 3 for storage and transportation.

These relationships required for the frame to articulate as described are explained further with reference to FIG. 5B. In FIG. 5B and equations below, each pair of capital letters represents the length of a linear strut segment having its opposite end points located at the pivot points corresponding to the location of the capital letter used to identify each end of the segment. In other words, the length of each strut segment represented in the equations below is measured from the pivot point at a first end (indicated by the first capital letter of the segment name) to the pivot at an opposite second end (indicated by the second capital letter of the segment name). Thus, in FIG. 5B, each capital letter represents the pivot point associated with a particular frame strut 22,72 at the indicated hub or other pivot location (or at a different corresponding location), depending upon which strut is being referenced. It can be seen that the following relationships must be maintained for the frame 20 to articulate:

$$JL+LK=FL+LG=IE+ET=FE+EG=TH+HI=CD+DB \quad \text{Equation 1}$$

$$KL+LF=JL+LG=TE+EG=IE+EF=TH+DB=IH+DC \quad \text{Equation 2}$$

$$HA+AD=HR+RD \quad \text{Equation 3}$$

$$AH+HR=AD+DR \quad \text{Equation 4}$$

In addition to the above, for any given row RW of parallel, spaced-apart linkages 50,70, an axis of rotation or axis of articulation AX (for primary scissor linkages 50) and AX1, AX2 (for double-scissor linkages 70) must be maintained along the entire length of the row RW, meaning that for any given row of parallel, spaced-apart linkages 50,70 none of the primary (conventional) scissor linkages 50 can be replaced with a double-scissor linkage 70 (or vice versa) without replacing all of the primary (conventional) scissor linkages 50 with a double-scissor linkages 70 in the same row RW of linkages, as there would be pivot pin locations on the double-scissor linkages 70 that would not be present on the primary scissor linkages 50.

Use of the double-scissor segments 70 also allows for wall sections 30s or roof sections 40s to have different lengths than widths, i.e., to be rectangular but not square. In the illustrated example, the use of the double-scissor segments 70 provides for an increased eave height EH without increasing the length 50L of each roof segment 50 as would greatly increase the overall roof height RH at its peak.

FIG. 5A is view of detail "5A" of FIG. 1 and partially shows a double-scissor linkage segment 70. FIG. 5A shows 10 an example of a hard stop knee hinge 80 that can be used to provide the third and fourth pivot points P3,P4 of the 15 accommodating linkage AK. The illustrated hard stop knee hinge 80 includes a first or lower portion 82 connected to another one of the struts 72 that defines a projecting tab or 20 tongue 86 that is closely slidably received in the slot 82s. A pivot pin pivotally connects the tab 86 to the walls 82w and 25 captures the tab 86 in the slot 82s to define the third and fourth pivot points P3,P4. The walls 82w of the slot 82s prevent undesired lateral flexing of the struts 72 relative to each other (the walls 82w confine movement to rotational 30 movement about the pivot point P3,P4), and hard contact 35 between an end 86s of the tongue 86 and the lower knee hinge portion 82 defines a stop ST that prevents over (hyper) extension of the struts 72 relative to each other, i.e., the stop ST blocks pivoting movement of the tab 86 relative to the slot 82s at a select angular orientation when the third and fourth pivot points P3,P4 are moving toward each other when the frame 20 is erected. Alternatively, a hard stop can be provided by other contact between the first and second hinge portions 82,84 such as contact outside the slot 82s and/or by hard contact between at least two struts 72. It is not intended that the present development be limited to the hinge example shown in FIG. 5A, and any other suitable hinge structure can be used for providing the pivot points P3,P4.

FIG. 6 shows detail "6" of FIG. 1 with the shelter frame 40 20 in its partially erected/deployed configuration. The frame 20 comprises an optional ground strap cinch system 90 according to an embodiment of the present invention. The ground strap cinch system 90 is provided to facilitate the 45 assembly of the outer hubs 60a located along the length FL of the frame 20 on its opposite lateral sides 20c,20d. During erection of the shelter 10, these laterally outermost hubs 60a have heretofore been difficult to assemble by connecting the upper hub portion 62 to the hub post 66 as required and assembling these outer hubs 60a is an important part of 50 erecting the frame 20. According to the illustrated embodiment of the present frame 20 and shelter 10, each outer hub 60a comprises a ground strap cinch system 90 including a flexible cinch member 92 such as a strap, rope, cable, chain, and/or a combination of same and/or any other elongated 55 flexible member. The flexible cinch member 92 includes an inner end or other inner portion 92a that is fixedly connected to one of the upper and lower hub portions 62,64. In the illustrated example of FIG. 6, the inner end 92a is secured to the lower hub portion 64 using a sewn loop in the flexible 60 cinch member 92 that is engaged with a pin or other structure of the lower hub portion 64. The flexible cinch member 92 is also threaded between the upper and lower hub portions 62,64 in a block-and-tackle or similar back-and-forth arrangement to provide mechanical advantage. As 65 shown herein, the cinch member 92 extends from the hub portion 62,64 to which it is connected (lower hub portion 64 in the present example—referred to as a "first" hub portion)

to the other, opposite hub portion **62,64** (upper hub portion **62** in the present example—a “second” hub portion) where it is slidably or otherwise movably engaged with said second hub portion **62** and the cinch member **92** then extends back to the first hub portion **64** again where it is slidably or otherwise movably engaged with said first hub portion **64** such that tension applied to the free portion of the cinch member **92** that extends from the first hub portion causes the cinch member **92** to draw the upper and lower hub portions **62,64** together and toward each other such that the hub post **66** can be fitted into the upper hub portion **62**. The inner end **92a** of the cinch member **92** can alternatively be fixedly secured to the upper hub portion **62** in which case the upper hub portion **62** is the first hub portion and the lower hub portion **64** is the second hub portion. A pulley or other friction reducing roller or bushing **96** can be provided at the upper and/or lower hub portions **62,64** where the strap **92** changes direction. A free end **92b** of the strap **92** is pulled by a user to draw the upper hub portion **62** into engagement with the hub post **66** projecting from the lower hub portion **64** (see FIG. 4). In the present embodiment, the double-scissor linkage **70** goes “over-center” when the upper hub portion **62** engages the hub post **66** such that the upper hub portion **62** stays in engagement with the post **66** until manually disengaged therefrom when the frame **20** is manually collapsed. Alternatively, a lock pin or other fastener can be used to secure the upper hub **62** to the hub post **66** once they are engaged. The free ends **92b** of straps or other cinch members **92** located on opposite lateral sides **20c,20d** of the frame **20** can be connected together with clips, a buckle or the like to prevent the opposite lateral sides **20c,20d** of the frame **20** from spreading apart from each other. In another alternative embodiment, the straps or other cinch members **92** are connected to and/or integrated into a floor covering **FC** that covers the ground **GR** inside the shelter (see also FIG. 1).

FIG. 7 is an end view of an alternative shelter **10** provided in accordance with an embodiment of the present invention including the outer shell **S** and optional inner liner **LN** made from canvas or another flexible fabric or membrane, and including a dynamic liner cinching system **100**. FIG. 8 illustrates an embodiment of the dynamic liner cinching system **100**. The liner **LN** is suspended from the frame **20** (e.g., from the upper hub portion **62** of multiple hubs **60**) by straps **102**. Preferably, the liner **LN** is connected to the frame **20** when the frame is only partially erected which requires a certain amount of slack in the liner. To prevent the excess slack in the liner **LN** when the frame **20** is fully erected, the dynamic liner cinching system **100** is provided. The liner includes first and second wall portions **LW**. The liner cinching system **100** includes a plurality of strap cinches **104** spaced along the length of each liner wall portion **LW** and along the length **FL** of the frame **20**. Each strap cinch **104** comprises a first loop or ring **105a** connected to the liner wall **LW**, a second loop or ring **105b** releasably connected to the frame **20** by a connector **108** such as a snap hook connector or the like, and a flexible strap **106** (which can comprise a flat or cylindrical or otherwise shaped web, cord, or other member). The strap **106** includes a first end **106a** fixedly secured or connected to the first ring **105a**. The strap **106** extends from the first end **106a** slidably through the second ring **105b** and then slidably through the first ring **105a**. A second end or other portion **106b** of the strap **106** spaced from the first end **106a** is preferably connected to the liner wall **LW** such that the weight of the liner wall pulls the strap **106** downward in the direction **D1** such that the first ring **105a** is pulled or drawn toward the second ring **105b** as

indicated by the arrow **TF** to correspondingly pull or draw the inner liner **LN** toward the second ring **105b** and outwardly toward the frame **20**. The first and second loops/rings **105a,105b** can each be made from any suitable material such as metal, a polymeric material, wood, a fabric webbing or cord, or other suitable material. In one embodiment, the strap connector **108** is connected to an upper hub portion **62** of the frame **20** using a ring **100R** (see FIG. 10) or the like so that the tension on the strap **106** further serves to urge the upper hub portion **62** toward the lower hub portion **64**, but the strap connector **108** can be connected to any other suitable location on the frame **20**. As noted, the strap **106** is threaded and connected as shown in FIG. 8 and as described so that downward movement **D1** of the liner wall **LW** by gravity or other force when the frame **20** is fully erected results in and causes an outward pulling or tensioning force **TF** being exerted on the liner **LN** to pull the liner outwardly toward the frame **20** and remove slack from the liner **LN**. The liner wall **LW** can be manually pulled downward **D1** and fastened to the frame **20** or ground **GR** or secured with weights, clips, or the like in such position to maintain the tension force **TF** on the liner **LN**. The liner wall **LW** can also optionally be connected to the optional floor covering **FC** (see also FIG. 1).

The hubs **60** of the frame are preferably constructed as shown in FIGS. 9 & 10. In particular, the upper hub portion **62** includes a cylindrical or other cup-like receiver **62R** that closely receives the projecting end **66E** of the hub post **66**. The hub post end **66E** and the receiver **62R** can each have any desired shape such as cylindrical, square, triangular, etc. Preferably, the post end **66E** and receiver **62R** are shaped to correspond with each other to minimize movement of these components relative to each other in any direction except axial movement along the longitudinal axis of the hub post **66** required to assemble or disassembly the hub **60**. As noted above, the end **66E** of the post **66** is held in the receiver **62R** without fasteners when the linkages **50, 70** go over-center when the frame **20** is fully erected, although a pin or other fastener can alternatively be used to secure the post end **66E** in the receiver **62R**.

As shown in FIGS. 11A and 11B, the shelter frame **20** optionally comprises at least one or a plurality of folding or pivoting thresholds **110**. FIG. 11A shows the pivoting threshold **110** in its extended (down) position and FIG. 11B shows the pivoting threshold **110** in its retracted (up) position. When a wall section **30s** is used as a door opening **DO** for movement of people and equipment into the shelter **10**, a conventional scissor linkage segment **50** that extends horizontally across the wall section **30s** adjacent the floor or ground **GR** defines a door threshold that can obstruct the door opening and that can be damaged and present a trip hazard. To overcome this drawback, a frame **20** provided in accordance with the embodiment of the present invention shown in FIGS. 11A & 11B includes a folding threshold **110**. The folding threshold comprises a threshold scissor linkage **50T** that is identical to the primary scissor linkage **50** except that first and second struts **122a,122b** (generally **122**) of the folding scissor linkage **50T** are respectively pivotally connected at their respective first ends to a first adjacent hub **60a1** by a threshold hinge **110H** comprising first and second hinges **112** such as pins or the like that respectively pivotally connect the first and second struts **122a,122b** to the hub **60a1**. The opposite second ends of the first and second struts **122a,122b** are releasably abutted with or connected to a second adjacent hub **60a2**, e.g., using respective latches **114** or the like. After the frame **20** is erected and secured in position, the second ends of the struts **122** at the second end

11

of the threshold segment **50T** spaced from the threshold hinge **110H** are disconnected from the second hub **60a2** and the threshold segment **50T** is pivoted upward at the threshold hinge **110H** as indicated by the arrow U until the threshold segment **50T** lies adjacent the vertical frame segment **70**, and the pivoting threshold segment is then secured in such position adjacent the vertical frame segment **70**. No parts are separated from the frame **20** during such pivoting of the threshold segment **50T** to prevent loss of frame components. In all embodiments, the frame **20** can optionally include wire or cable stays **23** that extend diagonally between hubs **60** and that are arranged in an X pattern in non-doorways on the left and right walls **30a,30b** to keep the frame **20** from "racking" or tilting to one side or the other.

The disclosure has been described with reference to several embodiments. Modifications and alterations will occur to others upon the reading and understanding of this specification. It is intended to include all such modifications and alterations insofar as they come within the scope of the appended claims or the equivalents thereof.

The invention claimed is:

1. An articulating frame for a shelter, said articulating frame comprising:
  - a plurality of struts pivotally connected to each other to define a skeletal structure that is adapted to be articulated between a folded condition and an erected condition, said skeletal structure in said erected condition comprising a segmented arch that defines an interior space, said segmented arch skeletal structure adapted to support an associated outer shell covering;
  - 35 said frame comprising a plurality of primary scissor linkage segments each comprising two primary struts of said plurality of struts pivotally connected together at an inner pivot point;
  - 35 said frame further comprising at least one double-scissor linkage segment comprising four elongated struts of said plurality of struts, said four elongated struts being longer than said primary struts and including: (i) first and second elongated struts each comprising opposite inner and outer ends, said first and second elongated struts being pivotally connected to each other at a first pivot point located between their respective inner and outer ends; (ii) third and fourth elongated struts each comprising opposite inner and outer ends, said third and fourth elongated struts being pivotally connected to each other at a second pivot point located between their respective inner and outer ends;
  - 40 said inner end of said first elongated strut being pivotally connected to said inner end of said third elongated strut at a third pivot point and said inner end of said second elongated strut being pivotally connected to said inner end of said fourth elongated strut at a fourth pivot point such that a four-bar parallelogram accommodating linkage is defined by said four elongated struts between said first pivot point, said second pivot point, said third pivot point, and said fourth pivot point;
  - 45 wherein an outer end of said at least one double-scissor linkage segment is connected to an outer hub and an inner end of said at least one double-scissor linkage segment is connected to an inner hub, said inner and outer hubs each comprising: (i) an upper hub portion; (ii) a lower hub portion spaced-apart from said upper hub portion; and, (iii) a hub post that extends between said upper hub portion and said lower hub portion;
  - 50 said first and second elongated struts of said double-scissor linkage respectively pivotally connected to said upper and lower hub portions of said outer hub at fifth and sixth pivot points;
  - 55 said third and fourth elongated struts of said double-scissor linkage respectively pivotally connected to said upper and lower hub portions of said inner hub at seventh and eighth pivot points;
  - 60 wherein at least one of said plurality of primary scissor linkage segments is pivotally connected to said upper and lower hub portions of said inner hub.
2. The articulating frame for a shelter as set forth in claim 1, wherein:
  - 15 a first distance is defined between the fifth pivot point and the first pivot point;
  - a second distance is defined between the sixth pivot point and the first pivot point;
  - a third distance is defined between the seventh pivot point and the second pivot point;
  - a fourth distance is defined between the eighth pivot point and the second pivot point;
  - the first distance+the second distance=the third distance+the fourth distance.
3. The articulating frame for a shelter as set forth in claim 2, wherein:
  - 25 the first distance+the fourth distance=the second distance+the third distance.
4. The articulating frame for a shelter as set forth in claim 3, wherein:
  - 30 a fifth distance is defined between the first pivot point and the third pivot point;
  - a sixth distance is defined between the first pivot point and the fourth pivot point;
  - a seventh distance is defined between the second pivot point and the third pivot point;
  - an eighth distance is defined between the second pivot point and the fourth pivot point;
  - the fifth distance+the sixth distance=the seventh distance+the eighth distance; and
  - the sixth distance+the eighth distance=the fifth distance+the seventh distance.
5. The articulating frame for a shelter as set forth in claim 1, wherein one of the upper and lower hub portions of the outer hub is a first hub portion and the other of the upper and lower hub portions of the outer hub is a second hub portion, and wherein said frame further comprises a ground strap cinch system comprising a flexible cinch member connected to the first hub portion and threaded from said first hub portion to said second hub portion and back again to said first hub portion such that tension applied to a free end of said flexible cinch member draws the first and second hub portions toward each other.
6. The articulating frame for a shelter as set forth in claim 5, wherein at least one of the first and second hub portions comprises a roller with which said flexible cinch member is engaged.
7. The articulating frame for a shelter as set forth in claim 6, wherein said flexible cinch member is connected to a floor covering that is adapted to cover a ground surface on which said frame is supported.
8. The articulating frame for a shelter as set forth in claim 1, further comprising an outer shell covering connected to said skeletal structure.
9. An articulating frame for a shelter, said articulating frame comprising:
  - 65 a plurality of struts pivotally connected to each other to define a skeletal structure that is adapted to be articu-

13

lated between a folded condition and an erected condition, said skeletal structure in said erected condition comprising a segmented arch that defines an interior space, said segmented arch skeletal structure adapted to support an associated outer shell covering; 5
 said frame including at least one double-scissor linkage segment, said at least one double-scissor linkage segment comprising four of said plurality of struts, said four struts including: (i) first and second struts each comprising opposite inner and outer ends, said first and second struts bring pivotally connected to each other at a first pivot point located between their respective inner and outer ends; (ii) third and fourth struts each comprising opposite inner and outer ends, said third and fourth struts being pivotally connected to each other at a second pivot point located between their respective inner and outer ends; 10
 said inner end of said first strut being pivotally connected to said inner end of said third strut at a third pivot point and said inner end of said second strut being pivotally connected to said inner end of said fourth strut at a fourth pivot point such that a four-bar parallelogram accommodating linkage is defined by said four struts between said first pivot point, said second pivot point, said third pivot point, and said fourth pivot point; 15
 said articulating frame further comprising an inner liner suspended from the frame, said liner comprising a liner cinching system comprising:
 a first ring connected to a liner wall of the liner; 20
 a second ring releasably connected to the frame; 25
 a strap including a first end fixedly secured to the first ring and extending from the first end slidably through the second ring and then through the first ring, said strap further comprising a portion spaced from the first end that is connected to the liner wall whereby downward movement of said liner wall exerts a tensioning force on said strap such that the first ring is drawn toward the second ring and said inner liner is drawn outwardly 30
 toward said frame. 35

10. The articulating frame for a shelter as set forth in claim 9, wherein said second ring is connected to a snap hook connector that is releasably connected to said frame. 40

14

11. An articulating frame for a shelter, said articulating frame comprising:
 a plurality of struts pivotally connected to each other to define a skeletal structure that is adapted to be articulated between a folded condition and an erected condition, said skeletal structure in said erected condition comprising a segmented arch that defines an interior space, said segmented arch skeletal structure adapted to support an associated outer shell covering; 5
 said frame including at least one double-scissor linkage segment, said at least one double-scissor linkage segment comprising four of said plurality of struts, said four struts including: (i) first and second struts each comprising opposite inner and outer ends, said first and second struts bring pivotally connected to each other at a first pivot point located between their respective inner and outer ends; (ii) third and fourth struts each comprising opposite inner and outer ends, said third and fourth struts being pivotally connected to each other at a second pivot point located between their respective inner and outer ends; 10
 said inner end of said first strut being pivotally connected to said inner end of said third strut at a third pivot point and said inner end of said second strut being pivotally connected to said inner end of said fourth strut at a fourth pivot point such that a four-bar parallelogram accommodating linkage is defined by said four struts between said first pivot point, said second pivot point, said third pivot point, and said fourth pivot point; 15
 wherein said third and fourth pivot points comprise respective knee hinges, each of said knee hinges comprising:
 a first portion comprising a slot defined between first and second lateral walls; 20
 a second portion comprising a projecting tab that is closely slidably received in the slot; and,
 a pivot pin that pivotally captures the tab in the slot. 25
 12. The articulating frame for a shelter as set forth in claim 11, wherein hard contact between said tab and said first portion of said knee hinge provides a hard stop that blocks pivoting movement of the tab relative to the slot at a select angular orientation. 30
